UNITED STATES PATENT OFFICE.

FRANK F. SOMMERS, OF DETROIT, MICHIGAN.

MATCH-GATHERING MACHINE.

SPECIFICATION forming part of Letters Patent No. 637,041, dated November 14, 1899.

Application filed June 26, 1897. Serial No. 642,382. (No model.)

To all whom it may concern:

Be it known that I, FRANK F. SOMMERS, a citizen of the United States, residing at Detroit, county of Wayne, State of Michigan, 5 have invented a certain new and useful Improvement in Match-Gathering Machines; and I declare the following to be a full, clear, and exact description of the invention, such as will enable others skilled in the art to which 10 it pertains to make and use the same, reference being had to the accompanying drawings, which form a part of this specification.

This invention relates to a match-gathering machine, and has for its object an improved 15 machine to gather matches from the dipping-bar and deliver them in trays straight and with heads all at one side of the tray ready to be taken out in masses for the final boxing.

One object of my invention is to deliver 20 the large number of matches falling at once from the dipping-bar to the machine in two or more evenly-distributed portions, so that the proper action of the machine shall not be interfered with by too many matches being 25 fed to it at once.

With the machine which embodies this invention the matches are gathered with great rapidity—so quick that the entire two thousand five hundred contained in the frame of 30 dipping-bars is dropped into the tray, sorted, and arranged almost instantly, the gathering of the entire two thousand five hundred not requiring more than a second or two of time and without any liability of burning any of 35 the matches, which may always be left until fully dried before they are gathered.

In the drawings, Figure 1 is a perspective showing the top, front, and left side of the machine. Fig. 2 is a perspective showing the 40 top, rear, and right side. Fig. 3 is a detail of the tray holder and shaker. Fig. 4 is a longitudinal and vertical section of the machine. Fig. 5 is a longitudinal section of the receiving-tray and adjacent parts. Fig. 6 is 45 a detail view, partly in section, of the shaft R and clutching apparatus. Fig. 7 is an elevation showing the clutching-faces of the pulleys, and Fig. 8 is a section on the line x x of Fig. 7.

50 That end of the machine at which the tray 18, Fig. 1, is located will be considered the front.

A indicates the framework, at one end of which is journaled a shaft S, that carries the main driving-wheel B and a drum t, a belt-pulley t', and a wiper-cam t''. At the other end of the frame is a shaft R, that carries two loose pulleys r' r'', a toothed pinion r'', and a clutch-wheel r''. At this end of the machine there is also a second shaft T, that carries a drum t'', Fig. 4, and there is also at this end of the frame a third shaft H, that carries a stretcher-drum h. Around the drums t, t'', and h is a carrier apron or belt h'. The upper surface of this belt travels in a substantially horizontal course near the upper end of the frame and just below a number of guide-strips 2. These guide-strips are disposed across the frame above the belt h' and extend lengthwise of the frame parallel with the line of travel of the belt. They hang closely adjacent to the upper surface of the belt and do not obstruct its free motion. They are supported from the arms 2' 2'', Fig. 1, and from a bar 3, that passes through the side pieces of the frame 75 near the rear of the machine. The space between adjacent guide-bars is considerably less than the length of a match. Above the guide-bars 2, resting on the sides of the main frame, is a second frame C, divided by both longitudinal and cross bars into a number of vertical passage-ways 6^a 6^b. The space included between the cross-bars is in each instance so small that a match dropped into it from above can pass through it only in a substantially 80 vertical line and cannot fall either sidewise nor lengthwise of the machine, but must pass substantially vertically down through it. Under the passage-ways 6^b are traps 5. As shown in the drawings, there are traps at one-half 85 of the openings 6^a 6^b. Said passage-ways and the traps 5 are so disposed that there is at front of the machine a line of open passage-ways 6^a across it, with a line of passage-ways 6^b, underneath which there is a trap 5, next 90 following, with a third line of openings 6^a next back of this open at the bottom, and so on to the rear of the machine. By closing alternate rows of said passage-ways when the matches are dropped from the dipping-bar 95 and opening the closed passage-ways after the matches which pass through the open passage-ways have been disposed of by the machine 100 the matches are delivered to the machine in

evenly-distributed portions, so that the action of the machine is not liable to be clogged.

The traps 5 are hinged to the auxiliary frame C at their rear edges and are arranged 5 to drop when the support which holds them up is removed.

Underneath the frame C is a slide 7, arranged to reciprocate between the front and rear of the auxiliary frame. It is actuated 10 by a pinion r^3 that gears into a rack 7^a . The pinion r^3 is on the shaft R, and this shaft is driven in its backward movement by the belt 8 and belt-wheel r^2 . The actuation is primarily from the main shaft; but there is an 15 intermediate pulley 9 and a small pulley on the same shaft with the pulley 9, (but not shown,) so that the backward movement of said rack is comparatively slow, the speed between the driving-shaft and the pulley r^2 being reduced. The reverse movement returning the slide 7 to the front of the machine is a rapid motion communicated to the shaft R from the main shaft S by a direct belt, by 20 which the relative speed of the two shafts is not so greatly reduced. As the slide 7 is moved backward it allows the traps 5 to fall, and this opens a clear passage-way for those of the matches which have been temporarily held in the passage-ways 6^b . The slide 7 carries 25 at its front end a T cross-piece 7^b , from which there projects downward a number of pins 7^c , that straighten any match that may accidentally have fallen across the upper edge of the guide-bars 2.

31 is a cross-piece on the slide 7, located toward the rear of said slide.

The slide 7 after moving to the extent of its backward travel is automatically reversed by the shifting of the clutch r^4 , which during 40 the backward movement has been in engagement with the pulley r^2 and at the end of the backward movement of the slide shifts into engagement with the pulley r' . To bring about this engagement between the clutch 45 and the two pulleys, there is a bent lever 8^d , one end of which, 8^a , Fig. 1, is provided with a forked terminal that engages with the groove in the shifting clutch r^4 . The other end of the lever passes across the main frame, and 50 said lever or a projection therefrom lies in the path of fingers 7^d and 32, that project from the cross-pieces 7^b of said slide, one finger 32 engaging it on the forward movement and another finger 7^e engaging it on the return movement. The finger which engages the 55 free end of the lever 8^d on the backward movement of the slide shifts the clutch which had previously been in engagement with the pulley r^2 out of engagement with that pulley and 60 into engagement with the pulley r' . On the return movement of the slide the finger which engages the free end of the lever shifts the clutch out of engagement with the pulley r' , but the free end of the lever is itself caught 65 by the riser 30 of a stepped slot 10 in the frame, and the clutch stops after it has passed out of engagement with the pulley r' and be-

fore it has engaged again with the pulley r^2 . When in this position, both the pulleys r' and r^2 are loose from the shaft and the slide is 70 not actuated, although the belt is moving and the shaking device to be hereinafter described is in operation. The clutch is brought into engagement with the pulley r^2 by lifting the free end of the lever above the riser 30 and 75 swinging the lever along the slot 10 to accomplish the clutch. The shifting from the pulley r^2 to the pulley r' is automatic and takes place at the end of the backward travel of the slide 7. The reverse shifting of the clutch 80 to uncouple it from the pulley r' at the end of the forward travel of the slide 7 is also automatic, but the completion of the shift and the engagement of the clutch with the pulley r^2 are not automatic. 85

At the front end of the machine there is a shaking-holder in which the receiving-tray is held, which holds and shakes the tray with a motion parallel to the motion of the belt, shaking the matches as they accumulate in 90 the tray with an end shake. The mechanism for shaking is shown in Figs. 1, 3, and 4.

11 11 indicate brackets which reach forward from the frame and support a rocking frame 12 on journal-pins 13 13^a. The bracket 95 also supports adjustable limiting-blocks 15 16 15^a 16^a and a tabular plate 17, adapted to hold a removable tray 18. The swinging table or frame supported on the rock-arm 12 is normally held forward against the blocks 15 100 16 by a spring 17^a, one end of which engages the rock-arm. In order to shake it or rock it backward, there is secured to the table a flat leaf-spring 19, which extends to the rear and terminates with a curve that projects under the wiper-cam t^3 .

As the shaft S revolves the cam t^3 engages in the curved terminal of the spring 19 and rocks the rock-arm and the table supported thereby backward until the cam rotates out of engagement with the end of the spring 19. This backward rock of the table has strained the spring 17^a, and the spring 17^a instantly retracts the table when the cam passes out of engagement with the curved part of the spring 110 19. This shaking motion produced by drawing the table in one direction with the rotating cam and drawing it in the other direction with a spring produces a series of short quick jerks that act very effectively to straighten 115 the matches down in proper shape.

Within the tray I employ an attachment which aids greatly in straightening the match-splints in the tray. It consists of a frame 21, with cross-partitions 22 and with that side 125 against which the heads of the matches impinge as they drop off from the belt h' inclined so that the bottom of the side 20 extends farther forward than the top. The matches dropping against this partially-hooded frame fall 130 straight between the partitions, with the heads lying against the side 20 and the splints lying across the tray. The tray 18 and frame 21 are held firmly on the table 17 by clips 33,

which are secured to said table and engage over the upper edge of said frame. The further operation of packing the matches in boxes is performed after the tray, with its contents, 5 is removed from the shaking-table and the attachment taken off from above it, leaving the tray filled with the straightened and properly-disposed matches.

The matches in the frame of dipping-bars 10 are held firmly by catches that hold the bars, and when the dipping-frame is placed over the auxiliary frame C, with the dipped ends of the matches downward, the bars are compressed in the first instance by means of a 15 screw-actuated head 24. After being slightly compressed the hooks or catches are released and the screw 25 turned to retract the head 24 and loosen the bars that hold the matches. The matches immediately drop from between 20 the bars of the dipping-frame, part of them dropping entirely down onto the belt h' , by which they are carried immediately to and delivered into the tray. Another part are obstructed in their downward movement by the 25 traps 5 and are only dropped as the traps are successively opened by the retraction of the slide under them. Thus the belt does not receive matches in quantities great enough to overload it when the dipping-frame is first 30 opened, and the subsequent action of the machine in delivering the second portion of the matches to the tray is so much quicker than the action of the attendant in taking them off of the dipping-bars and placing another 35 set of dipping-bars over the machine that no time is lost.

What I claim is—

1. In a match-gathering machine, a frame, C, a plurality of vertical passage-ways through 40 said frame, a delivery-belt beneath said passage-ways, adapted to receive the matches that pass through said passage-ways, traps, 5, adapted to close alternate passage-ways, and means for actuating said traps at the time of 45 alternate deliveries of matches to said frame, substantially as and for the purpose described.

2. In a match-gathering machine, in combination with a framework, a belt and means 50 adapted to actuate the belt, guide-bars disposed longitudinally above the belt, a receptacle for the frame which holds the matches, guides adapted to direct the matches from the frame which holds them to the belt, a 55 cross-head, 7^b , pins, 7^c , extending from said cross-head between said guide-bars, and means for reciprocating said cross-head, substantially as and for the purpose described.

3. In a match-gathering machine, in combination with a framework, a receptacle for the frame which holds the matches, guideways adapted to direct the matches from the frame which holds them to the gathering mechanism, hinged traps adapted to obstruct a portion of said guideways when closed, and a cross-head, 7^b , movable below said guideways and adapted to close said traps and hold them

closed when moved in one direction, and to allow said traps to open when moved in the other direction, and means for reciprocating 70 said cross-head, substantially as shown and for the purpose described.

4. In a match-gathering machine, in combination with a framework, a belt and means adapted to actuate the belt, guide-bars disposed longitudinally above the belt, a receptacle for the frame which holds the matches, guideways adapted to direct the matches from the frame which holds them to the belt, hinged traps adapted to obstruct a portion of said 80 guideways when closed, a cross-head, 7^b , movable below said guideways and adapted to close said traps and hold them closed when moved in one direction, and to allow them to open when moved in the other direction, said 85 cross-head being provided with pins, 7^c , extending from said cross-head between said guide-bars, and means for reciprocating said cross-head, substantially as shown and for the purpose described. 90

5. In a match-gathering machine in combination with a framework, a belt and means adapted to actuate the belt, guide-bars disposed longitudinally above the belt, a receptacle for the frame which holds the matches, 95 guideways adapted to direct the matches from the receptacle which holds them to the belt, a cross-head, 7^b , fingers, 7^c , extending from said cross-head between said guide-bars, a rack extending from said cross-head, a pinion, r^3 , engaging with said rack, a clutch mechanism adapted to control the motion of said pinion, a lever adapted to shift said clutching mechanism and a finger, 32 , extending from said rack, said lever being so 105 disposed as to be actuated by said fingers at opposite ends of the travel of said cross-head, substantially as and for the purpose described. 100

6. In a match-gathering machine, in combination with a framework, a receptacle for the frame which holds the matches, guideways adapted to direct the matches to the gathering mechanism, hinged traps adapted to obstruct a portion of said guideways when 110 closed, and a cross-head, 7^b , movable below said guideways and adapted to close said traps and hold them closed when moved in one direction, and to allow them to open when moved in the other direction, a rack extending 115 from said cross-head, a pinion, r^3 , engaging said rack, a clutching mechanism adapted to control the motion of said pinion, a lever adapted to shift said clutching mechanism, and lugs or fingers, connected with said 120 rack and cross-head, said lever being so disposed as to be actuated by said fingers, at opposite ends of the travel of said cross-head, substantially as and for the purpose described. 125

7. In a match-gathering machine, in combination with a delivery-belt, h' , a drum, t , a rocking frame located adjacent to the delivery end of said belt, and to said drum, a 130

spring acting to urge said frame toward one end of its travel, a cam, 18, upon the shaft of said drum, a resilient arm, 19, extending from said rocking frame into the line of movement 5 of said cam, whereby said cam is caused to rock said frame in a direction opposite to the action of said spring, and to release said frame, substantially as and for the purpose described.

- 10. 8. In a match-gathering machine, in combination with a delivery-belt, a tray, 18, adapted to receive the matches from said belt, said tray being provided with a side, 20, opposite to said belt, said side sloping away from said 15 belt from above downward, substantially as shown and described.
- 9. In a match-gathering machine, in combi-

nation with a delivery-belt, 14, drum, 15, rocking frame located adjacent to the delivery end of said belt, means for reciprocating said rocking frame in the direction of the motion of said belt, and a tray, 18, secured to said rocking frame, said tray having that one of its sides which is opposite and farthest away from said belt, sloping from above downward 25 in a direction away from said belt; substantially as shown and described.

In testimony whereof I sign this specification in the presence of two witnesses:

FRANK F. SOMMERS.
